LINE-SPACING MECHANISM

Charles B. Letterman, Hartford, Conn., assignor to Underwood Corporation, New York, N. Y., a corporation of Delaware

Application December 29, 1953, Serial No. 400,871

4 Claims. (Cl. 197—114)

This invention relates to typewriters and similar machines, and more particularly to line-spacing devices therefor. Such devices conventionally embody a pawl which is operable to engage and advance an element having a succession of line-spacing teeth, such as a line-space ratchet wheel, a desired number of teeth. It is also conventional to have in association with such devices provision whereby the advanceable element is stopped against overthrow through momentum.

It is a general object of the invention to provide an efficient line-spacing device embodying particularly a low-cost, reliably functioning and rugged space regulating and overthrow suppressing structure.

Other objects and features of the invention will be in part obvious and in part pointed out particularly as the following description of a preferred embodiment of the invention proceeds.

In the drawings:

Figure 1 is a sectional side elevation showing a paper-supporting carriage of a typewriter embodying the mechanism of the invention in normal position, the section being taken just inside of the right-hand carriage end,

Figure 2 is a plan view showing the left-hand portion of the carriage,

Figure 3 is a sectional side elevation similar to Figure 1 but the line-spacing mechanism is shown set for and actuated to obtain a triple line-space advance,

Figure 4 is a front-sectional elevation of the mechanism seen in Figure 2,

Figure 5 is a side elevation illustrating the mechanism of the invention set for and actuated to obtain a single-tooth line space,

Finally, Figure 6 shows in enlarged aspect an active contact relation of a line-space pawl with a line-space wheel.

Now referring generally to the drawings, a usual cylindrical paper feeding roll or platen 10 carries at the left end thereof concentrically thereon a line-space wheel 11 having a succession of teeth 12 preferably of saw-tooth form. For purposes of the present invention said line-space wheel 11 may be regarded to be unitary with the platen 10. Each end of the platen is flanked by a carriage end 13, the left one of such ends only being shown. At each end of the platen a short shaft 14 is extended therefrom and is rotatably accommodated in the respective carriage end. The outer ends of the shafts 14 have each a turning knob 15.

The line-space wheel 11 has associated therewith a line-space pawl 16 which by a pin 17 is pivotally carried on a disk 20 constituting a driver, such driver having a circumferential fit at 19 directly adjacent the line-space wheel 11 for swinging operation on the platen in concentric relation therewith.

The disk 20 has leftwardly extending therefrom an element 21 that operates in a downreaching fork 22 of a member 23 which by means of pins 24 has pivotal support upon two vertically spaced outwardly reaching branches 25 of the left carriage end 13. The pins 24 afford for

said member 23 a pivot axis which extends generally vertically through the axis of rotation of the platen and said member 23, for free accommodation of the platen shaft, is perforated at 27. The member 23 is part of an operable structure including also a forwardly reaching operating lever 28 ending in a finger piece, not shown.

A spring 29, see particularly Figures 2 and 4, constantly urges the member 23 with its operating lever 28 clockwise, a stop 30 of the disk 20 engaging normally a fixed pin 31 on the carriage end 13 to thereby determine for the disk 20 and the lever structure 23, 28 their normal positions.

The stated pin 31 has a reduced portion whereagainst a bevel on the feeding end of the pawl 16 normally lies to hold the pawl free of the line-space wheel 11, said pawl under the urge of a spring 33 having anchorage on the disk 20 being biased toward the line-space wheel 11.

A detent roll 34 on an arm 35 that is under the urge of a spring 36 serves to detain the line-space wheel in different line-space positions. The said roll 34 is adapted to be moved clear of the line-space wheel by a throw-off lever 37 by camming action on a face 38 of said arm 35.

The pawl 16 includes a rearwardly reaching nose 40, substantially in the path of operation of the pivot pin 17. In the path of operation of said nose 40 there lies a pivotally settable member 41 carried on a pintle 42 having pivotal support in a boss 39 on the carriage end 13. The stated pivotal member 41 is settable to three different angular positions under control of a handle 43, the latter having a collar 44 whereby it is borne fast on the pintle 42. Said member 41 is provided with three notches 47 that are angularly spaced about the axis defined by the pintle 42 and which are radially disposed variously distant from such axis. By appropriately setting said member 41 angularly, any one of the three notches 47 is adapted to be brought into the operating path of said nose 40. The bases of the several notches 47 afford stopping abutments 48 for engagement by the extremity of the nose 40, and depending on the setting given the member 41, said pawl is operable the appropriate extent to feed the line-space wheel 11 exactly an integer of one, or two, or three teeth. As the nose 40 clashes with any one of the abutments 48, the line space wheel 11 and platen 10 associated therewith tend to overthrow by force of momentum. However, the cooperation of the nose 40 with the member 41 in the entered notch 47 is such that the pawl 16 is interlocked with the member 41 to block or suppress outward displacement of the pawl. Specifically referring to Figures 3, 4 and 5, it will be noted that the pawl nose 40 contacts the entered notch 47 at points A and B, such points with respect to the pivot axes of either said pawl 16 or the member 41 being at different distances from such axes, and moreover at opposite sides of the entered notch. The condition is such that there exists a lever-interlock between the member 41 and the pawl 16 which blocks outward movement of the feeding end of said pawl 16 away from the wheel 11. Inasmuch as the pawl is so held against outward movement, it follows that any wheel tooth 12 tending up pass it is restrained from doing so and it follows also that the wheel 11 is effectively held against overthrow.

It is to be noted further that as the line-space lever 28 is released and the pawl 16 under the urge of the spring 29 is drawn in reverse direction, the feeding end of the pawl 16 must be free to glide reversely over the tooth immediately trailing it.

From Figures 3 and 5, it will be seen that the lower side of the pawl nose 40 has only contact at B in the notch 47 into which it has entered to the limit of the abutment 48, and that in the restoring direction of the pawl 16 the lower side of the entered notch 47 tapers away from the nose toward the line-space wheel 11. This

3

tapering away allows the nose 40 to disengage itself freely from the stated lever-interlock with the member 41 when the feeding end of the pawl 16 in returning and bypassing the first tooth 12 is displaced upwardly and the nose 40 consequently swings downwardly.

The upper side of each of the notches 47 need only engage the nose 40 at the point A, and may be fully clear of the nose intermediate such point and the abutment 48. The handle 43 by which the member 41 is settable has a downwardly reaching extension or arm 50 which is flexible somewhat endwise of the carriage. Said arm 50 near its lower end has facing toward the adjacent carriage end 13 a blister 51 adapted to enter any one of three indentations 52 provided on a carriage-supported detent plate 53. Said plate 53 is accommodated between the carriage side wall 13 and the handle 43, and is pivotally carried on the pintle 42 for adjustment concentrically thereabout for properly correlating the position of the notches 47 with the pawl nose 40. Said plate 53 is secured in adjusted position by a clamping screw 54 entering a slot 55 in the plate and screwed into the carriage end 13.

Having specifically described the invention in a preferred form, what is claimed is:

1. A line-spacing mechanism for a typewriter or the like, comprising in combination, an element having a succession of line-spacing teeth and being advanceable in a direction of succession of such teeth, a pivotal pawl actuatable to advance said element in said direction by driving engagement with the teeth thereof and to ratchet in a reverse direction idly over such teeth, means comprising a pivotal support for said pawl, actuatable and restorable respectively to actuate and return said pawl, a member pivotally settable to different angular positions, a pivotal support for said member, and abutment means oppositely on said pawl and said member engageable in the different settings given to the latter to limit the actuation of said pawl to give different integers of tooth advances to said element, said abutment means being arranged so that in all movement limits reached by said pawl there exists an appreciable distance between the said two pivotal supports, said member and said pawl having in each of the movement limits reached by said pawl co-acting contacting faces at two different locations intermediate said pivotal supports to provide final lever-interlocks therebetween which will hold the pawl positively in toothed mesh with said element to suppress overthrow of the latter, said contacting faces arranged to allow reverse movement of said pawl over said teeth at the restoration of said actuatable means.

2. A line-spacing mechanism for a typewriter or the like, comprising in combination, an element having a succession of line-spacing teeth and being advanceable in a direction of succession of such teeth, a pivotal pawl actuatable to advance said element in said direction by driving engagement with the teeth thereof and to ratchet in a reverse direction idly over such teeth, means comprising a pivotal support for said pawl, actuatable and restorable respectively to actuate and return said pawl, a member pivotally settable to different angular positions, a pivotal support for said member, and means oppositely on said pawl and said member engageable in the different

angular settings given to the latter to limit the actuation of said pawl to give different integers of tooth advances to said element and additionally to engage said pawl with said member in a lever-interlock at two different locations intermediate said pivotal supports, said engageable means comprising oppositely on said pawl and said member nose means and notch means.

3. A line-spacing mechanism for a typewriter or the like, comprising in combination, an element having a 10 succession of line-spacing teeth and being advanceable in a direction of succession of such teeth, a pivotal pawl actuatable to advance said element in said direction by driving engagement with the teeth thereof and to ratchet in a reverse direction idly over such teeth, means comprising a pivotal support for said pawl, actuatable and restorable respectively to actuate and return said pawl, a nose unitary with said pawl, a pivoted stop member engageable by said nose to terminate the actuation of said pawl and settable to different angular positions, and 20 a pivotal support for said member, said member provided with a plurality of angularly spaced notches substantially radially to its pivotal support, abutments being afforded severally by the bases of said notches, for engagement by said nose to limit variously the actuation of said pawl in conformance with desired integers of required tooth advances of said element, said nose when engaging any of said abutments having opposite contact with said member in the entered notch at two points intermediate the said two pivotal supports to hold the 30 pawl in overthrow-preventing mesh with the toothed element, said notches relatively to said nose being formed to allow reverse movement of the pawl over said teeth.

4. A line-spacing mechanism for a typewriter or the like, comprising in combination, a toothed line-space 35 wheel, a pull-type pawl actuatable to turn said wheel in advance direction by driving engagement with its teeth and to ratchet in reverse direction over such teeth, means comprising a pivotal support for said pawl, actuatable and restorable respectively to actuate and return said pawl, a nose reaching out from said pawl generally in the actuating direction thereof, a member pivotally settable to different angular positions, and a pivotal support for said member disposed generally in the direction in which said nose moves at actuation of said pawl, said 45 member for each possible angular setting thereof being provided with a notch for the nose to enter thereinto at the actuation of said pawl; said notches disposed on said member so that for the different settings given to said member the nose is arrested when the line space wheel 50 has received a different integer of tooth advance and said nose, at arrest by the said member in each notch, having contact in such notch at opposite sides thereof at two different locations between the two pivotal supports in a manner to lock said nose against movement toward the line-space wheel.
